UNITED STATES PATENT OFFICE.

WILLIAM J. SELLECK, OF RIVERSIDE, CONNECTICUT.

AUTOMATIC CAR-LOADING APPARATUS.

No. 824,826.

Specification of Letters Patent.

Patented July 3, 1906.

Application filed October 10, 1904; Serial No. 227,837.

To all whom it may concern:

Be it known that I, WILLIAM J. SELLECK, a citizen of the United States, residing at Riverside, county of Fairfield, State of Connecticut, have invented a certain new and useful Improvement in Automatic Car-Loading Apparatus; and I declare the following to be a full, clear, and exact description of the invention, such as will enable others skilled in the art to which it pertains to make and use the same, reference being had to the accompanying drawings, which form a part of this specification.

My invention relates in general to loading apparatus, and more particularly to apparatus for automatically loading material upon moving cars.

In loading material, such as coal, upon cars it has heretofore been necessary to stop each car in proper position relatively to the loading apparatus and allow it to remain stationary while being filled. Such an operation requires considerable time, as it is necessary that each car should be located in an exact position to receive the material and remain in such position while receiving the material.

The object of my invention is to provide a loading apparatus by means of which moving cars may be successively filled with material automatically as they pass a given point without requiring them to stop.

A further object of my invention is to provide a loading apparatus for automatically delivering material to moving cars which will be automatically rendered inoperative when the supply of material is exhausted.

A still further object of my invention is to provide an apparatus for automatically loading material upon moving cars which will be comparatively simple in construction, strong and durable in use, and efficient in operation.

My invention, generally described, consists in a chute, a measuring-receptacle for receiving the material from the chute, a motor for oscillating the receptacle to deliver the material therefrom into a passing car, mechanism actuated by a trip on a car for operatively connecting the motor to the measuring-receptacle to oscillate the latter, and means actuated by the material in the chute for connecting said mechanism with the motor and for disconnecting said mechanism, and thereby interrupting the operation

of the apparatus when there is insufficient material in the chute to fill the measuring-receptacle.

My invention will be more fully described hereinafter with reference to accompanying drawings, in which the same is illustrated as embodied in a convenient and practical form, and in which—

Figure 1 is an elevational view; Fig. 2, a plan view; Fig. 3, a plan view from beneath the chute; Fig. 4, a sectional view on line 4 4, Fig. 3; Fig. 5, a sectional view on line 5 5, Fig. 3; Fig. 6, a sectional view on line 6 6, Fig. 5; Fig. 7, a sectional view of the chute and measuring-receptacle on line 7 7, Fig. 2; Fig. 8, a sectional view on line 8 8, Fig. 7; Fig. 9, a sectional view on line 9 9, Fig. 7; Fig. 10, a detail view of the car-tripping mechanism; Fig. 11, an enlarged sectional view of the shaft interposed between the car-tripping mechanism and the motor-clutch; Fig. 12, a detail sectional view on line 12 12, Fig. 3; and Fig. 13, a sectional view on line 13 13, Fig. 5.

The same reference characters are used to designate the same parts in the several figures of the drawings.

Referring to Fig. 1, reference-letter A designates a tie upon which is supported the rails *a* of a track.

A' designates a car of the self-dumping type, the trucks *a'* of which engage the rails *a* of the track.

*a*² indicates a bracket rigidly secured to and projecting laterally from the car *A'*, designed to engage and put in operation mechanism for filling the car with a predetermined material.

Reference characters *B'*, *B*², and *B*³ indicate vertical posts which support in an elevated position above the railroad-tracks the loading apparatus. *B*⁴ and *B*⁵ designate horizontal beams, such as channel-bars, which are supported by the posts *B'* *B*² at a height slightly above the tops of the cars. Suitable struts are provided for rigidly securing the horizontal beams *B*⁴ and *B*⁵ to the posts—such, for instance, as the channel-bars *b*³ *b*⁴, which extend downwardly from the posts *B'* and *B*² to the ends of the beams *B*⁴ and *B*⁵ at the rear of the track, and channel-beams *b*¹ *b*², which extend from the posts *B'* *B*² to the horizontal beams *B*⁴ and *B*⁵ at points above the track. Other suitable braces,

such as b^5 , (see Fig. 1,) may be provided where necessary to impart to the supporting structure the requisite strength.

C designates a hopper into which material is delivered from any ordinary supply—such, for instance, as coal-pockets. C' designates a chute leading in an inclined direction from the hopper C. The chute C' extends between and is supported by the posts B' and B² in any suitable manner. The lower end of the chute terminates adjacent to the outer surface of a drum D. An opening is formed through the drum D of a size corresponding to the cross-section of the chute. Located within the drum is a measuring-receptacle d, the opening into which registers with the opening through the drum, as clearly shown in Fig. 7. The top of the chute adjacent the drum is closed by an upwardly-yielding cover C², hinged at its upper edge to the top wall of the chute and provided with side wings C³, extending within and lying adjacent to the side walls of the chute. In order that there may be no opening between the bottom of the chute and the surface of the drum, an extensible strip C⁵, preferably angular in cross-section, is secured beneath the chute by means of slots and bolts and is projected against the surface of the drum by one or more springs c⁶, surrounding bolts C⁶, interposed between the strip C⁵ and an angular strip c⁵, rigidly secured to the under surface of the chute, as clearly shown in Fig. 7.

The ends D' and D² of the drum are provided with concentric journals d' and d², which are rotatively supported in bearings e' e², fixed upon the horizontal beams B⁴ and B⁵, the ends of the journals d' and d² projecting beyond the bearings therefor and provided with gear-wheels E' and E², which mesh with larger gear-wheels F' and F², fixed upon the ends of a shaft F, the latter being suitably journaled in bearings f, secured to the beams B⁴ and B⁵. The gear-wheels F' and F² are provided with wrist-pins, to which are pivotally connected links f' and f², the opposite ends of such links being pivotally connected to crank-arms G' and G², respectively, projecting from a crank-shaft G, the latter being journaled in bearings g, fixed upon the horizontal beams B⁴ and B⁵.

The power-shaft H is journaled in bearings h, fixed upon the horizontal beams B⁴ and B⁵, and is provided with a gear-wheel H³, which meshes with a larger gear-wheel G³, fixed upon the crank-shaft G. Any suitable motive power may be employed for rotating the power-shaft H—such, for instance, as a vertical engine w, the shaft W of which is rotatively connected to the power-shaft H by means of meshed gear-wheels W' and H', mounted, respectively, upon the engine-shaft and power-shaft.

In order that the engine or other motor may run constantly and only be effective to

rotate the drum D when a car is in position to receive the coal or the material therefrom, the following clutching mechanism is employed: A shaft M is journaled at one end in a bearing n', depending from a beam B¹¹, the opposite ends of the latter being rigidly supported by the transverse beams B⁷ and B⁸. The other end of the shaft M is journaled in a bearing n, mounted upon a supporting-block N, the latter being rigidly secured to the beam B¹¹. A crank-arm K' is fixed to the shaft M and is connected, by means of a rod k', with a short lever K, the latter being pivotally mounted at its lower end in a bracket b¹⁰, depending from an angular beam B¹⁰. The upper end of the lever K is provided with an antifriction-roller, which is adapted to ride upon a cam-track g³, rigidly secured to the spokes of the gear-wheel G³, as clearly shown in Figs. 5 and 6.

A second crank-arm L is fixed to the shaft M and extends at an approximately right angle to the crank-arm K'. The outer end of the crank-arm L is pivotally connected to a vertical rod L', which projects upwardly through the hole in a boss l³ on the end of the lever L³ and also through the hole in a boss on one arm of a bell-crank lever L², as will be understood by reference to Fig. 5. A weight l depends from the end of the crank-arm L, which serves to oscillate the shaft M, so as to throw the upper end of the lever K toward the gear-wheel G³.

The lever L³ is pivotally supported upon a lug depending from a casting O', the latter being supported by the block N. The bell-crank lever L² is also pivotally supported upon the casting O'. A vertically-reciprocating rod O extends through alined holes in brackets o' and o², which project from the casting O'. The lower end of the rod O is provided with a recess into which extends the end of the lever L³. A spacing-tube l' surrounds the rod L' and is interposed between the alined bosses on the lever L³ and L².

Splined upon the power-shaft H is a clutch H², having laterally-projecting inclined teeth h², adapted to engage co-operating teeth h', fixed to the gear-wheel H', the latter being loosely journaled upon the shaft H. A cam o projects laterally from a radial flange around the periphery of the clutch member H² and is adapted to be engaged by the upper end of the rod O, as shown in Fig. 5, to disengage the teeth on the clutch member from the teeth on the gear-wheel H'. A circular groove is formed in the clutch member H², into which extend the inwardly-projecting ends of a yoke l², the latter being rigidly secured to and forming part of the bell-crank lever L².

A third crank-arm m projects upwardly from and is rigidly secured to the shaft M and is provided with a hole through its upper end. A rod M' extends through a hole in the arm

m and is provided with an enlargement or nut on its end, between which and the arm *m* is interposed a coil-spring *m'*. The opposite end of the rod *M'* is pivotally connected to a crank-arm *P'*, rigidly secured to a shaft *P*, the latter being journaled in bearings and mounted upon the beams *B* and *B'*, which project laterally from the horizontal beam *B*, as clearly shown in Fig. 3. Loosely mounted upon the opposite end of the shaft *P* from the crank-arm *P'* is a collar *T*, having a laterally-projecting semicircular lug, as clearly shown in Fig. 11. Depending from the collar *T* is a hanger *T'*, the lower end of which is pivotally connected to a horizontal shoe *U*. A second hanger *T'* for supporting the shoe *U* depends from a rod *t*, suitably supported, as, for instance, in a bearing *t*, secured to the upper surface of the beam *B'*. The other end of the rod *t* may be conveniently supported in a strut *b*, which extends from the end of the beam *B* across the beam *B'*, to which it is rigidly secured. The shoe *U* is preferably provided with an extensible portion *u*, by means of which the length of the shoe may be adjusted to insure the operation of the loading apparatus at the instant the car is in position to receive the material from the measuring-receptacle *d*.

Surrounding and splined upon the shaft *P* is a sleeve *P*, one end of which has fixed thereon a collar *T'*, having a laterally-projecting semicircular lug adapted to coöperate with the lug on the collar *T* to non-rotatively lock the hanger *T'* to the shaft *P*. A disk *p* surrounds and is secured to the end of the sleeve *P* opposite the collar *T'*, while a similar disk *p'* loosely surrounds the shaft *P* adjacent to crank-arm *P'*. A collar *r* loosely surrounds the shaft *P*, between which and the end of the sleeve *P* is interposed a coil-spring *R*. Tie-rods *p* (see Fig. 3) connect the disks *p* and *p'*.

The bell-crank lever *S* is journaled upon a rod *s*, the latter being shown in Fig. 1 as journaled upon the strut *b* and extending through a bearing *s* upon the beam *b*, and the upper end of one of the arms of the bell-crank lever is bifurcated, so as to extend on opposite sides of the shaft *P* at a point intermediate of the disk *p'* and collar *r*. The other arm of the bell-crank lever *S* is connected by a rod *S'* to a crank-arm *S*, which is rigidly secured to a shaft *S*. The shaft *S* extends through the chute *C'*, near the upper end thereof. The shaft *S* is journaled in brackets *s*, secured to the inner surface of the top of the chute, as shown in Figs. 7 and 9, and is also journaled in a bearing *s*, mounted upon a beam *S*, which projects laterally from a beam *b* of the supporting structure. Depending from and rigidly secured to the shaft *S* within the chute is a gate *C*, the latter adapted to be swung upwardly by the material in the chute, and thereby rock the shaft *S*.

Rigidly secured to the end *D* of the drum is a disk *D*, around which extends a brake-band *d*. One end of the brake-band is rigidly secured to a pin *d*, (see Fig. 4,) and the other end is pivotally connected to a lug *d* projecting from a collar *f*, the latter being loosely supported upon the shaft *F*. Extending from and rigidly secured to the collar *f* is a lever *F*. The free end of the lever *F* projects above the shaft *G* and is adapted to be engaged by either one of two cams *g* and *g'*, which project radially from and are rigidly secured to the shaft *G*. The cam *g* is slightly longer than the cam *g'*, as will be seen by reference to Fig. 4.

A hood *C* is preferably located partially around the drum *D* and is supported upon curved beams *c* and *c'*, which project upwardly from the beams *B* and *B'* and are secured at their upper ends to the inclined beams *b* and *b'*. The upper end of the hood *C* is secured to a transverse angle-bar *C*, mounted at its opposite ends upon the supports *c* and *c'*. In order to give sufficient rigidity to the supports *c* and *c'*, a transverse angle-bar *c* extends across the same, the latter being rigidly secured at its ends to vertical bars *c* and *c'*, which project upwardly from the inclined strut *b* and *b'*. The lower end of the hood *C* is extended downwardly below the beam *B*, as shown at *V*, to form a deflector for directing the material into the car. A similar guide or deflector *V* extends beneath the drum and is supported by suitable strips *v* and *v'*, depending from the horizontal beams *B* and *B'*.

In order to prevent the rotation of the shaft *G* after it has rotated the desired amount to bring the receptacle *d* into alignment with the chute, lugs *n* and *n'* project from the ends of the crank-arm *G* and *G'* and are adapted to be received in recesses formed in vertical leaf-springs *n* and *n'*, respectively, the latter being mounted in vertical channel-bars *N* and *N'*, which are rigidly secured to bars *N* and *N'*, projecting from and supported by the horizontal beams *B* and *B'*.

The operation of my invention is as follows: The coal or other material deposited in the hopper *C* passes into the chute *C'*, thence into the measuring-receptacle *d* in the drum *D*. The material within the chute *C'* elevates the gate *C* therein, so that the shaft *S* is oscillated, thereby swinging upwardly the crank-arm *S*, which, through the interposed rod *S'*, oscillates the bell-crank lever *S* in a direction to force the collar *r* on shaft *P* toward the left in Figs. 1 and 11. The movement of the collar *r* through the interposed spring *R* slides the sleeve *P* upon the shaft *P*, so that the semicircular lugs on the collar *T* and *T'* are brought into engagement, thereby locking the hanger *T'* to the shaft *P*. The passage of a car beneath the shoe *U* causes the bracket *a* on the car to engage the

shoe and swing the same in the direction in which the car is moving. The shaft P is consequently rocked and the crank-arm P' thereon partially rotated, so that a tension is applied to the rod M', which, through its engagement with the arm m, oscillates the shaft M. The oscillation of the shaft M swings upwardly the crank-arm L thereon, thereby rocking the levers L³ and L² through the medium of the rod L' and interposed tube l'. The movement of the lever L³ withdraws the rod O from the path of the cam o, while the oscillation of the bell-crank lever L² forces the clutch members H² toward the gear-wheel H' through the engagement of the yoke l' with the groove in the clutch member. The teeth h² are consequently forced into engagement with h' and the gear-wheel H' rigidly connected to the shaft H. Rotary motion is consequently imparted to the shaft H from the motor n, and such rotary motion is transmitted to the shaft G through the meshed gear-wheels H³ and G³. The respective directions of rotation of the gear-wheels is indicated by arrows in Fig. 1, by which it will be seen that the rotation of the shaft G swings downwardly the crank-arms G' and G², thereby partially rotating the gear-wheels F' and F², which through the gear-wheels E' and E² oscillate the drum through approximately two hundred and ten degrees, so that the opening of the measuring-receptacle d occupies a position above the car and the material therefrom is deposited into the car, passing between the deflectors V and V'.

The oscillation of the shaft M swings the lever K away from the cam-guide g³, so that the rotation of the gear-wheel G³ brings the cam-guide beneath the roller k and retains the lever K, and consequently the shaft M through the connecting-rod k', in the positions to which they have been moved by the shoe U—namely, in position to clutch the gear-wheel H' to the shaft H and continue the operation of the apparatus sufficiently to impart two revolutions to the shaft H, which, as the periphery of the gear-wheel H³ is one-half that of the periphery of gear-wheel G³, effects one complete rotation of the shaft G. The size of the gear-wheels F' and F² relatively to the meshed gear-wheels E' E² is such that the rotation of the shaft G through one hundred and eighty degrees oscillates the gear-wheels F' and F² sufficiently to rotate the drum the desired amount to bring the opening of the measuring-receptacle from its position in alinement with the chute to a position above the car. The continued rotation of the shaft G through one hundred and eighty degrees oscillates the gear-wheels F' and F² in a reversed direction, and such reversed direction is communicated to the gear-wheels E' and E², so that the drum is re-

turned to its first position, in which the opening of the measuring-receptacle alines with the chute.

Immediately upon the shaft G completing a revolution the lever K is disengaged from the cam-guide g³ and swung toward the gear-wheels by the weight l through the interposed crank-arms L and K', shaft M, and connecting-rod k'. The oscillation of the shaft M, due to the weight l, draws downwardly the rod L', which oscillates the lever L³ and forces upwardly the rod O, so that the upper end thereof is projected in the path of the cam o, and the latter, through engagement with the upper end of the rod O, forces the clutch member H² away from the gear-wheel H', thereby disengaging the teeth h² from the teeth h'. The motor is therefore disconnected from the shaft H, and the drum remains in position for the measuring-receptacle to receive material from the chute until the bracket on another car engages the shoe U and again puts the apparatus into operation.

In order to insure the drum stopping in the position in which the mouth of the receptacle d alines with the chute, the cam g³ is provided on the shaft G, which engages the outer end of the lever F³ and oscillates the latter, so that the brake-band d³ tightly engages the brake-disk D³ and immediately stops the rotation of the drum. The cam g' on the shaft G is shorter than the cam g³, as it engages the lever F³ when the drum has been rotated to dump the material from the receptacle. It is not necessary that the brake-band should bind upon the brake-disk with the same force when the drum is in position to dump the material as it is when the drum is rotated to bring the receptacle into alinement with the chute, inasmuch as when the drum is rotated to dump the material the shaft G has completed one-half revolution and the drum cannot therefore rotate farther, and it is merely necessary that the brake-band should relieve the strain upon the machinery which would otherwise result from the stopping of the rotation of the drum in one direction and the commencement of its reversed rotation. On the other hand, when the drum has been rotated into position for the receptacle to receive material from the chute the clutch has been disengaged, so that if it were not for the operation of the brake-band the drum would from its own momentum rotate farther than necessary, and consequently the mouth of the receptacle would not accurately aline with the chute.

In order to insure the complete stoppage of all of the parts of the apparatus, except the engine and gear-wheel H', the lugs n⁵ and n⁶ on the ends of the crank-arms G' and G² are provided, which engage within the grooves in the spring-plates n³ and n⁴ immediately upon the operation of the brake-band by the cam

g^2 , thereby preventing any rebounding of the parts.

When there is no longer any material in the chute, the gate C^7 falls by gravity to the position shown in Fig. 7, thereby oscillating the shaft S^3 and swinging downward the crank-arm S^2 thereon, so that the spring R is permitted to expand thereby through the interposed bifurcated end of the bell-crank lever S , the disk p' and the tie-rods p moving the sleeve P^2 toward the right and disengaging the lugs on the collars T^1 and T^2 . The hanger T^4 may then swing idly upon the shaft P until the shoe U is engaged by the bracket a^2 on the passing car. Immediately upon coal being deposited in the chute the gate C^7 is swung upwardly and the hanger T^4 clutches to the shaft P through the interposed mechanism.

In order to avoid damage to the upper wall of the chute by means of lumps of coal or other material being forced against the lower edge thereof by the lower wall of the receptacle d , the swinging cover C^2 is provided, which merely swings upwardly to permit the material to pass with the drum out of the chute. The depending wings C^3 prevent material falling over the sides of the chute when the cover C^2 is swung upwardly. A close contact is always maintained between the outer surface of the drum and the lower edge of the bottom of the chute owing to the spring-pressed plate C^5 .

It is necessary that the shoe U should be so placed with respect to the drum that after the car has actuated the shoe the drum will be oscillated and the material delivered therefrom at the exact instant the car is in position to receive the same. The adjustable end u of the shoe permits such a timing of the operation of the mechanism as to insure the rotation of the drum and the dumping of the material from the receptacle therein at the exact instant the car is in position to receive the same.

From the foregoing description it will be observed that I have invented an improved apparatus for automatically loading material upon a passing car, the operation of which is automatically discontinued when the supply of material is exhausted. It is obvious that my invention is capable of use wherever coal or other material is to be handled, both in connection with cable-cars employed for transferring coal from one point to another and in the loading of freight-cars as well.

While I have described more or less precisely the details of construction, I do not wish to be understood as limiting myself thereto, as I contemplate changes in form, the proportion of parts, and the substitution of equivalents as circumstances may suggest or render expedient without departing from the spirit of my invention.

Having now fully described my invention, what I claim as new, and desire to secure by Letters Patent, is—

1. In an automatic loading apparatus, the combination with a receptacle for receiving material from a supply thereof and delivering the same to a conveyance, of a motor for operating said receptacle to receive and discharge material, and means actuated by a conveyance moving relatively to said receptacle for controlling the operation of said receptacle by the motor.

2. In an automatic loading apparatus, the combination with a receptacle for receiving material from a supply thereof and delivering the same to a conveyance, of a motor for operating said receptacle to receive and discharge material, mechanism controlled by a conveyance moving relatively to said receptacle for operating the same to discharge material therefrom, and means for automatically rendering said mechanism inoperative when the supply of material is exhausted.

3. In an automatic loading apparatus the combination with a chute, of a rotary receptacle supported in position to receive the material from said chute, a motor controlled by an approaching car for oscillating said receptacle to discharge the material therefrom into the car and for oscillating said receptacle into position to again receive material from said chute.

4. In an automatic loading apparatus the combination with a chute, of a rotary drum closing the lower end of said chute and having an opening thereinto adapted to register with said chute, a motor controlled by an approaching car for oscillating said drum to bring the opening therein above the car, and for returning said drum in position for the opening therein to align with the chute.

5. The combination with a closed chute, of a rotary receptacle closing the lower end of said chute and having an opening therein adapted to register with the chute, an upwardly-swinging cover for said chute the lower edge of which lies adjacent to the outer surface of said receptacle, means operated by an approaching car for oscillating said receptacle to bring the opening therein above the car, and automatic means for returning said receptacle to its first position in which the opening therein aligns with the chute.

6. In an automatic loading apparatus the combination with a chute, of a rotary drum closing the lower end of said chute and having an opening therein adapted to register with said chute, a movable plate carried by the lower edge of the bottom of said chute, means for maintaining said plate in contact with the outer surface of said drum, means operated by an approaching car for oscillating said drum to bring the opening therein above the car, and automatic means for re-

turning said drum to its first position in which the opening therein alines with the chute.

7. In an automatic loading apparatus the combination with a chute, of a rotary drum closing the lower end of said chute and having an opening therein adapted to register with the chute, an upwardly-swinging cover for said chute the lower edge of which lies adjacent to said drum, a movable plate carried at the lower edge of the bottom of said chute, means for maintaining said plate in contact with the surface of said drum, means operated by an approaching car for oscillating said drum to bring the opening therein above the car, and automatic means for returning said drum to a position in which the opening therein alines with said chute.

8. In an automatic loading apparatus the combination with a chute, of a rotary receptacle closing the lower end of said chute and having an opening therein adapted to register with said chute, means operated by an approaching car for oscillating said receptacle to bring the opening therein above the car, automatic means for returning said drum to its first position, and automatic means for positively stopping the return movement of said receptacle when the opening therein alines with the chute.

9. In an automatic loading apparatus the combination with a chute, of a rotary receptacle closing the lower end of said chute and having an opening therein adapted to register with said chute, means operated by an approaching car for oscillating said receptacle to bring the opening therein above the car, automatic means for returning said drum to its first position, a circular flange carried by one end of said receptacle, a brake-band surrounding said flange, and automatic means for tightening said band around the flange to stop the return movement of said receptacle when the opening therein alines with the chute.

10. In an automatic loading apparatus the combination with a moving receptacle for receiving material from a supply thereof, a motor for moving said receptacle, and means actuated by an approaching car for operatively connecting said motor to said receptacle to move the latter into position to discharge the material therefrom into the car.

11. In an automatic loading apparatus the combination with a chute, of a movably-supported receptacle for receiving material from said chute, a motor for moving said receptacle relatively to the chute, means actuated by an approaching car for operatively connecting said motor to said receptacle to move the latter into position to discharge the material therefrom into the car, and automatic means for continuing the operation of said motor to return the receptacle into position to again receive material from said chute.

12. In an automatic loading apparatus the

combination with a chute, of a movably-supported receptacle for receiving material from said chute, a motor for moving said receptacle relatively to the chute, means actuated by an approaching car for operatively connecting said motor to said receptacle to move the latter into position to discharge the material therefrom into the car, automatic means for continuing the operation of said motor to return the receptacle into position to again receive material from said chute, means for disconnecting said motor from said receptacle when the opening in the latter alines with said chute, and means for positively stopping the movement of said receptacle when the motor is disconnected therefrom.

13. In an automatic loading apparatus the combination with a chute, of a movably-supported receptacle for receiving material from said chute, a motor for moving said receptacle relatively to the chute, means actuated by an approaching car for operatively connecting said motor to said receptacle to move the latter into position to discharge the material therefrom into the car, automatic means for continuing the operation of said motor to return the receptacle into position to again receive material from said chute, means for disconnecting said motor from said receptacle when the opening in the latter alines with said chute, a circular flange carried by one end of said receptacle, a brake-band surrounding said flange, and means for tightening said band around said flange when the motor is disconnected from said receptacle.

14. In a loading apparatus, the combination with a chute, of a rotary receptacle for receiving material from said chute, a crank-shaft, operative connections interposed between said crank-shaft and said receptacle whereby one revolution of said shaft partially rotates said receptacle to discharge material therefrom and returns said receptacle into position to receive material from said chute, mechanism for rotating said crank-shaft, and means for rendering said mechanism operative to rotate said shaft through a single revolution only.

15. In a loading apparatus, the combination with a chute, of a rotary receptacle for receiving material from said chute, a crank-shaft, operative connections interposed between said crank-shaft and said receptacle whereby one revolution of said shaft partially rotates said receptacle to discharge material therefrom and returns said receptacle into position to receive material from said chute, a motor for rotating said shaft, means actuated by an approaching car for operatively connecting said motor to said shaft, and automatic means for disconnecting said motor from said shaft when the latter has completed one revolution.

16. In a loading apparatus, the combina-

tion with a chute, of a rotary receptacle for receiving material from said chute, a crank-shaft, a crank-arm on said shaft, a link connected to said crank-arm, a gear-wheel to which the opposite end of said link is eccentrically connected, a second gear-wheel in mesh with said first gear-wheel and rigidly connected to said receptacle concentrically with the axis thereof, a motor for rotating said shaft, means for operatively connecting said motor to said shaft, and automatic means for disconnecting said motor from said shaft when the latter has completed one revolution, the relative sizes of said meshed gear-wheels being such that one revolution of said shaft partially rotates said receptacle to discharge the material therefrom and return said receptacle into position to receive material from the chute.

17. In a loading apparatus, the combination with a chute, of a rotary receptacle for receiving material from said chute, a crank-shaft, a crank-arm on said shaft, a link connected to said crank-arm, a gear-wheel to which the opposite end of said link is eccentrically connected, a second gear-wheel in mesh with said first gear-wheel and rigidly connected to said receptacle concentrically with the axis thereof, a motor for rotating said shaft, means for operatively connecting said motor to said shaft, and automatic means for disconnecting said motor from said shaft when the latter has completed one revolution, the relative sizes of said meshed gear-wheels being such that one revolution of said shaft partially rotates said receptacle to discharge the material therefrom and return said receptacle into position to receive material from the chute, a lug on the outer end of said crank-arm and a yielding stop located in position to engage said lug when the motor is disconnected from said shaft.

18. In a loading apparatus, the combination with a chute, of a rotary receptacle for receiving material from said chute, a crank-shaft, operative connections interposed between said crank-shaft and said receptacle whereby one revolution of said shaft will partially rotate said receptacle to discharge the material therefrom and return said receptacle into position to receive material from the chute, a power-shaft journaled parallel to said crank-shaft, meshed gear-wheels fixed upon said shafts, the periphery of the gear-wheel on the crank-shaft being twice that of the periphery of the gear-wheel on the power-shaft, a motor for rotating said power-shaft, means for operatively connecting said motor to said power-shaft, means actuated by a cam-guide on said crank-shaft for continuing said connection between the motor and power-shaft during one revolution of the crank-shaft, and means for disconnecting the motor from the power-shaft when the crank-shaft has completed one revolution.

19. In a loading apparatus, the combination with a chute, of a rotary receptacle for receiving material from said chute, a crank-shaft, operative connections interposed between said crank-shaft and said receptacle whereby one revolution of said shaft will partially rotate said receptacle to discharge the material therefrom and return said receptacle into position to receive material from the chute, a power-shaft journaled parallel to said crank-shaft, meshed gear-wheels fixed upon said shafts, the periphery of the gear-wheel on the crank-shaft being twice that of the periphery of the gear-wheel on the power-shaft, a motor for rotating said power-shaft, a clutch interposed between said motor and said power-shaft, means for operating said clutch to connect the motor to the power-shaft, a cam-guide fixed concentrically upon the gear-wheel of the crank-shaft for retaining said clutch in position to connect the motor to the power-shaft, and means for automatically operating said clutch to disconnect the motor from the power-shaft when the crank-shaft has completed one revolution.

20. In a loading apparatus, the combination with a chute, of a rotary receptacle for receiving material from said chute, a crank-shaft, operative connections interposed between said crank-shaft and said receptacle whereby one revolution of said shaft will partially rotate said receptacle to discharge the material therefrom and return said receptacle into position to receive material from the chute, a power-shaft journaled parallel to said crank-shaft, meshed gear-wheels fixed upon said shafts, the periphery of the gear-wheel on the crank-shaft being twice that of the periphery of the gear-wheel on the power-shaft, a motor for rotating said power-shaft, a clutch on said power-shaft for connecting the motor thereto, a controlling-shaft, a yoke actuated by an oscillation of said controlling-shaft to operate said clutch, a crank-arm on said controlling-shaft for oscillating the same to connect the motor to the power-shaft, means connected to said crank-arm for oscillating the controlling-shaft to clutch the motor to the power-shaft, a second crank-arm on said controlling-shaft, a cam-guide carried by the gear-wheel on the crank-shaft, means interposed between said second crank-arm and said cam for retaining the controlling-shaft in position to clutch the motor to the crank-shaft during one revolution of said shaft, and an unclutching device operated by the oscillation of the controlling-shaft when the cam-guide passes out of operative relation to said second crank-arm.

21. In a loading apparatus, the combination with a chute, of a rotary receptacle for receiving material from said chute, concentric spindles upon which said receptacle is journaled, gear-wheels fixed to the ends of said spindles, a counter-shaft, gear-wheels

- fixed to said counter-shaft in mesh with the gear-wheels on said spindles, a crank-shaft having crank-arms on the ends thereof, links connecting said crank-arms eccentrically 5 with the gear-wheels on said counter-shaft, the relation between said gear-wheels and crank-arms being such that one revolution of said crank-shaft partially rotates said receptacle to discharge the material therefrom and 10 returns the same into a position to receive material from said chute, and means for rotating said crank-shaft through one revolution and then discontinuing such rotation.
22. In a loading apparatus, the combination 15 with a chute, of a rotary receptacle for receiving material from said chute, concentric spindles upon which said receptacle is journaled, gear-wheels fixed to the ends of said spindles, a counter-shaft, gear-wheels 20 fixed to said counter-shaft in mesh with the gear-wheels on said spindles, a crank-shaft having crank-arms on the ends thereof, links connecting said crank-arms eccentrically with the gear-wheels on said counter-shaft, 25 the relation between said gear-wheels and crank-arms being such that one revolution of said crank-shaft partially rotates said receptacle to discharge the material therefrom and returns the same into a position to receive material 30 from said chute, means for rotating said crank-shaft through one revolution and then discontinuing such rotation, a circular flange carried by said receptacle a brake-band surrounding said flange, a lever fulcrummed upon said counter-shaft and operatively connected at one end to said brake-band and extending at its other end adjacent to said crank-shaft, cams carried by said crank-shaft for engaging said lever when said 35 receptacle completes its movement in each direction thereby causing said brake-band to bind upon said flange and positively stop the rotation of said receptacle in each direction.
23. In an automatic loading apparatus, the combination 40 with a chute, of a movable receptacle for receiving material from said chute, mechanism operated by an approaching car for moving said receptacle to discharge the material therefrom into the car, and means for automatically rendering said 45 mechanism inoperative when less than a predetermined amount of material is in said chute.
24. In an automatic loading apparatus, the combination 50 with a chute, of a movable receptacle for receiving material from said chute, mechanism operated by an approaching car for moving said receptacle to discharge the material therefrom into the car, a pivot- 55 ed gate depending within said chute and operative connections between said gate and said mechanism whereby when said gate occupies a substantially vertical position within 60 said chute said mechanism is rendered inoperative.
25. In an automatic loading apparatus, the combination with a moving receptacle for receiving material from a supply thereof, a motor for moving said receptacle, mechanism actuated by an approaching car for operatively connecting said motor to said receptacle to move the latter into position to discharge the material therefrom into the car, and means for automatically rendering said mechanism inoperative when the supply of 75 material is exhausted.
26. In an automatic loading apparatus, the combination with a chute, of a movably-supported receptacle for receiving material from said chute, a motor for moving said receptacle 80 relatively to the chute, a clutch for operatively connecting said motor to said receptacle to move the latter into position to discharge the material therefrom, a rock-shaft, connecting means interposed between said 85 rock-shaft and said clutch for actuating the latter to connect the motor to said receptacle, and an arm depending from said rock-shaft into the path of an approaching car.
27. In an automatic loading apparatus, the combination with a chute, of a movably-supported receptacle for receiving material from said chute, a motor for moving said receptacle relative to the chute, a clutch for operatively connecting said motor to said receptacle 90 to move the latter into position to discharge the material therefrom, a rock-shaft, connecting means interposed between said rock-shaft and said clutch for actuating the latter to connect the motor to said receptacle, an arm depending from said rock-shaft 95 into the path of an approaching car, a clutch for connecting and disconnecting said arm to said rock-shaft, and means for automatically unclutching said arm from the rock-shaft 100 when less than a predetermined amount of material is in the chute.
28. In an automatic loading apparatus, the combination with a chute, of a movably-supported receptacle for receiving material from 105 said chute, a motor for moving said receptacle relative to the chute, a clutch for operatively connecting said motor to said receptacle to move the latter into position to discharge the material therefrom a rock-shaft, connecting means interposed between said 110 rock-shaft and said clutch for actuating the latter to connect the motor to said receptacle, an arm depending from said rock-shaft into the path of an approaching car, a gate 115 depending within said chute, and operative connections between said gate and the clutch on said rock-shaft whereby said arm is disconnected from said rock-shaft when said gate occupies a substantially vertical position 120 within said chute.
29. In an automatic loading apparatus, the combination with a chute, of a movably-supported receptacle for receiving material from said chute, a motor for moving said recepta- 125

cle relatively to the chute to discharge the material therefrom, a clutch for operatively connecting said motor to said receptacle, a rock-shaft, connecting means interposed between said rock-shaft and said clutch, an arm loosely depending from said rock-shaft and extending into the path of an approaching car, a sleeve longitudinally movable upon said rock-shaft, coöperating clutch members carried by said arm and said sleeve, a bell-crank lever for moving said sleeve about said rock-shaft to engage and disengage said clutch members, and means for automatically oscillating said rock-shaft to disengage said clutch member when less than a predetermined amount of material is in said chute.

30. In an automatic loading apparatus, the combination with a chute, of a movably-supported receptacle for receiving material from said chute, a motor for moving said receptacle relatively to the chute to discharge the material therefrom, a clutch for operatively

connecting said motor to said receptacle, a rock-shaft, connecting means interposed between said rock-shaft and said clutch, an arm loosely depending from said rock-shaft and extending into the path of an approaching car, a sleeve longitudinally movable upon said rock-shaft, coöperating clutch members carried by said arm and said sleeve, a bell-crank lever for moving said sleeve about said rock-shaft to engage and disengage said clutch members, a pivoted gate depending within said chute, a rod operatively connecting said gate to said bell-crank lever whereby when said gate occupies a substantially vertical position within said chute, said clutch members are disengaged.

In testimony whereof I sign this specification in the presence of two witnesses.

WILLIAM J. SELLECK.
